PRINTING PRESSES

Joseph S. Chilton, Lamar, Colo.

Application June 2, 1954, Serial No. 433,923

1 Claim. (Cl. 271—22)

My invention relates to improvements in printing presses of the impression cylinder and reciprocating type bed class.

The primary object of my invention is to provide in a printing press having a type bed mounted to reciprocate forwardly and rearwardly through printing and idle strokes and novel means for raising and lowering the bed at the end of its strokes into and from printing position.

Another object is to provide in such a press a single belt drive operatively connecting the impression cylinder directly to the bed to reciprocate the bed upon rotation of the cylinder in opposite directions.

Still another object is to provide in such a press improved sheet feeding means operated by rotation of the impression cylinder accurately and obviating suction sheet pick up devices.

Still another object is to provide improved simply constructed inking means readily removable so that the press may be used with a stencil sheet as a duplicating press.

Still another object is to simplify such machines and reduce the cost of manufacturing and servicing the same.

Other and subordinate objects together with the precise nature of my improvements will become readily apparent when the following description and claim are read with reference to the drawings accompanying and forming part of this specification.

In said drawings:

Figure 1 is a view in side elevation of my improved press in the preferred embodiment and illustrating the parts positioned for a forward printing stroke of the type bed;

Figure 2 is a view in plan of the same partly broken away and drawn to a larger scale;

Figure 3 is a view in vertical longitudinal section taken on the line 3—3 of Figure 2 and drawn to the same scale as Figure 1;

Figure 4 is a view in vertical longitudinal section illustrating the manner in which the impression cylinder and type bed cooperate in printing;

Figure 5 is an enlarged view in vertical longitudinal section showing the position of the parts when the type bed has moved into its forward limit of movement, parts being broken away;

Figure 6 is an enlarged view in longitudinal section partly broken away and illustrating the manner in which the printed sheets are discharged and stacked;

Figure 7 is an enlarged view in vertical transverse section taken on the line 7—7 of Figure 3;

Figure 8 is an enlarged exploded view in perspective of the inking means and the operating roller for a sheet grip on the impression roller;

Figure 9 is an enlarged view in perspective of the type bed carriage;

Figure 10 is an enlarged view in perspective of the impression roller and the sheet grip thereon;

Figure 11 is an enlarged fragmentary view in transverse section taken on the line 11—11 of Figure 10;

2

Figure 12 is an enlarged view in perspective of the type bed;

Figure 13 is an enlarged view in perspective of a sheet releasing device forming part of the sheet feeding means; and

Figure 14 is an enlarged view in transverse section taken on the line 14—14 of Figure 13.

Referring now to the drawings by numerals, the press of my invention comprises an oblong horizontal base 1 hollow to reduce weight. An upwardly opening elongated channel member 3 surmounts the base 1 parallel therewith and forms a runway for a type bed and carriage presently described. Inverted transverse supporting channel bars 5, 7 at opposite sides of the transverse center of said channel member 3 are suitably fixed thereto under the same.

Pairs of coil springs 9, 11 at opposite sides of said channel member 3 interposed between the bottoms of said bars 5, 7 and the base 1 yieldingly support said channel members 5 and 7. Nut equipped bolts 13, 15 are suitably fixed in the bottom 17 of the channel member 3 and bars 5, 7 and slidably extend into the base 1 said bolts depending through the channel bars 5, 7 and springs 9, 11 and stabilizing said channel member against horizontal movement. The springs 9, 11 yieldingly support the channel member 3 for a particular purpose presently explained.

An impression cylinder 19, suitably fixed on an axial shaft 21 extends transversely of and above the channel member 3 in the transverse center thereof. The impression cylinder 19 is rotatably mounted between a pair of brackets 23 bolted, as at 25, to and upstanding from the base at opposite sides and in the transverse center thereof and in which opposite ends of the cylinder shaft 21 are suitably journaled. The impression cylinder is suitably resiliently faced as at 27 in any usual manner. A hand crank 29 is provided on one end of the shaft 21 for rotating the same to rotate said cylinder 19.

An oblong rectangular type bed 31 is mounted in the channel member 3 on a roller carriage 33 for end wise reciprocation with said carriage longitudinally of said member 3 beneath the impression cylinder 19 forwardly and rearwardly through printing and idle strokes respectively. As will be manifest printing is effected by type 35 in a conventional chase 37 suitably fixed on said bed 31 for coaction of the type and impression cylinder during the forward printing stroke of the type bed 31. Side guide rollers 39 on the type bed 31 engaging the sides 41 of the channel member 3 prevent lateral play of said bed 31.

The carriage 33 is of rectangular skeleton form with diagonal cross braces 43 extending between the sides 45 thereof and is supported at its ends on the bottom 17 of the channel member 3 by a pair of transverse front and rear rollers 47 rotatable on a pair of front and rear axle shafts 49 the opposite ends of which are suitably fixed in the sides 45 of carriage 33 and extend outwardly beyond said carriage for a purpose presently seen. A pair of front and rear transverse resilient bumper bars 51, 53 in opposite ends of the channel member 3 limit forward and return strokes of the carriage 33.

The type bed 31 is mounted for limited overthrow movement endwise on the carriage forwardly and rearwardly relative thereto when said carriage reaches the limits of its forward and rearward strokes. For this purpose a pair of longitudinal bottom side bars 55 on the type bed are provided which straddle the carriage and are supported on the ends of the axle shafts 49. Front and rear pairs of opposite elongated, bottom, cam notches 61, 63 in said bars straddle the ends of the axle shafts 49. The cam notches 61, 63 are provided with cam bottoms 65, 67 inclined from the horizontal so that

upon forward overthrow movement of the type bed 31 it will be lowered for a return idle stroke and upon rearward overthrow movement of said bed 31 it will be raised for a forward printing stroke.

The impression cylinder 19 is operatively connected to the type bed 31 by means of a cable 71 wound intermediate its ends on one end of said cylinder 19, as best shown in Figures 1 and 2, and extending oppositely from beneath said cylinder with opposite ends 73, 75 attached to the front and rear ends 65, 67 of said bed 31 by shackles 77, 79 adjustable in upstanding front and rear end ears 81, 83 on said bed. As will be seen the notches 61, 63 and axle shafts 49 provide lost motion driving connections between the type bed 31 and carriage 33.

The inking means is disposed at the rear of the impression cylinder 19 and comprises a cradle 85 including a pair of side cheek plates 87 pivoted on a front cross shaft 89 removably supported at its ends in the bearing brackets 23 so that said cradle 85 is disposed above the type bed 31 and type 35 to rock vertically. An inking roller 91 extending transversely of the type bed 31 above the type 35 is fastened on an axial shaft 93 journaled in the cheek plates 87 so that said roller may roll along the type 35. A pair of idler wheels 95 loose on the shaft 93 roll on the type bed 31 at opposite sides thereof and support the inking roller 91 in proper position to ink said type 35, said idler wheels 95 also supporting the cradle 57 against downward swinging during reciprocation of the type bed 31. The inking roller 91 is driven in the direction of rotation of the impression cylinder 19 by a belt 97 engaged with the cylinder 19 at the end thereof opposite the cable 71 and operating a pulley 99 fastened on one end of shaft 93.

An ink applying idler roller 101 extends along the top of the inking roller 91 and is adapted to be coated with ink manually by any suitable means. The ink applying roller 101 is hollow with end plugs 103 fixed thereon by set screws 105 and is endwise slidable on an axial shaft 107 having reduced squared ends 109 vertically slidable in upright forks 111 on cheek plates 87 so that said roller 101, under the influence of gravity frictionally rides and is rotated by the inking roller 91. Means are provided for reciprocating said roller 101 endwise along the inking roller 91 to facilitate the ink applying operation comprising a cylindrical core 113 in said roller 101 fixed by a set screw 115 to the shaft 107 and having cam ends 117 coacting upon rotation of said roller 101 with cam faces 119 on the plugs 103 to reciprocate said roller 101.

A pair of double hooks 121 suspended from a cross shaft 123 cross connecting said brackets 23 in the rear of the rollers 91, 95 are engageable with a cross shaft 125 rigidly connecting the cheek plates 87 at rear ends of said plates, the arrangement being such that said hooks 121 are engageable with said shaft 125 to latch the cradle 85 in upswung position with the inking roller 95 raised into ineffective position, or said hooks may be engaged with said shaft 125 to hold the cradle 87 in downswung position as shown in the drawings so that the weight of the cradle 87 will be taken off the wheels 95 during the inking operation.

The sheet feed means, designated generally by the numeral 129, comprises a rectangular tray 131 mounted above the ink applying roller 101 and in front of the impression cylinder 19 in downwardly and forwardly inclined position for gravity feed of sheets from a stack 133 therein. The tray 131 is mounted by means of an inverted U-shaped standard 135 rising from the bearing brackets 23 with a cross bar 137 supporting the lower end 139 of the tray. The stack 133 rests on the lower front end 139 of the tray.

A false bottom panel 143 in said tray 131 is spring tensioned at its front lower end toward an internal front, transverse lip 145 and yieldingly clamps lower leading ends of the sheets of the stack 133 between said panel

and lip so that the top sheet of the stack 133 must be lifted upwardly and released from beneath said lip 145 to release the same for feeding downwardly out of said tray 131.

Coil springs 147 between the false bottom panel 143 and the bottom 149 of tray 131 urge said panel 143 at its lower end toward said lip 145 into clamping position. The coil springs 147 are sleeved on rearwardly extending guide pins 151 on said panel 143 slidably extended through the bottom of the tray 131.

A sheet guiding flange 153 inclines downwardly and forwardly from the lip 145 between the ink applying roller 101 and the impression roller 19 to guide the released sheets to a sheet grip 155 on the impression cylinder 19 and presently described.

Sheet releasing means is provided comprising the following. A sheet releasing blade 157 of rubber or the like extending transversely over the front of the tray 131 is mounted for revolving into engagement with the top sheet of the stack 133.

The mounting for the blade 157 comprises a transverse shaft 159 at the front of the tray 131 journaled at its ends in bearing brackets 161 on the standard 135, a pair of collars 163 fixed by set screws 165 on said shaft 159 adjacent opposite ends thereof, and an elongated clip bar 167 straddling and detachably gripping a rounded longitudinally flanged rear edge 169 of said blade 157 and pivoted at its ends on lateral pins 171 on said collars. A one to one ratio sprocket and chain drive 173 between one end of shafts 21, 159 provides for rotating said shaft 159 to revolve said blade 157 in accordance with the direction of rotation of the impression cylinder 19 similarly.

A stop arm 175 on the blade 157 engages the shaft 159 when said blade 157 is revolved in one direction, i. e. counterclockwise as viewed in Figures 1, 3, 4, 5 and 6 and prevents said blade 157 from swinging counterclockwise on the pins 171 and thereby maintains said blade momentarily in position to frictionally engage and slide the top sheet of the stack upwardly against the rear upper end 177 of tray 131 to buckle the sheet, release the same from under lip 145 and then disengage the sheet for gravity feed thereof, as shown in Figure 6. When the blade 157 is revolved clockwise, the blade 157 swings idly against the top sheet of the stack.

The sheet grip 155 comprises a longitudinally extending clip bar 156 on the impression cylinder 19 forming therewith a clip and pivoted at its ends on said cylinder, as at 179, for swinging of one edge away from said cylinder into clip opening sheet releasing position. Springs, as at 181 on said pivots 179 interposed between said clip bar and cylinder 19 normally yieldingly hold said clip bar 156 in clip closing position with said edge of said bar 156 in sheet gripping relation to said cylinder 19. A clip bar pivoting and opening idler roller 183 on the before-mentioned shaft 89 engages and pivots said clip bar 156 into clip opening position as said grip 155 is revolved by the impression cylinder 19 into a position directly below the flange 153.

A pair of upper and a lower sheet discharge rollers 185, 187 extend in front of and parallel with the impression cylinder 19 for stripping printed sheets from said cylinder and discharging the same onto a table 189 suitably mounted on member 3 above the type bed 31. The lower discharge roller 187 is journaled at its ends in the bearing brackets 23, and is driven by the before-mentioned belt 97 which is operatively connected to one end thereof as best shown in Figure 2. The upper discharge rollers 185 are journaled in a pair of arms 193 pivoted on a cross shaft 191 on the brackets 23 so that said roller 185 engages the roller 187 by gravity.

A pair of sheet guides 195 on the arms 193 curve upwardly in front of the impression cylinder 19.

A suitable transverse sheet aligning stop bar 197 is provided on the table 189.

In operating my improved press, the impression cylinder 19 is rotated counterclockwise as indicated by the broken line arrow in Figures 1 and 3 to position the parts in starting position. Such rotation of the impression cylinder 19 causes winding and unwinding of the cable 71 on said cylinder so that end 73 of the cable pulls the type bed 31 into the limit of its rearward idle stroke, as shown in Figure 3. In its rearward stroke the type bed 31 pulls the carriage 33 rearwardly against the rear bumper bar 53 before said bed assumes its limit of rearward idle movement, and said bed 31 then moves through an overthrow phase of rearward movement during which notches 61, 63 coat with the axle shafts 49 to cam said bed upwardly into printing position, and limit its rearward overthrow movement as shown in Figure 3. In the limit of rearward overthrow movement of bed 31 the cable 71 limits counterclockwise rotation of impression cylinder 19. In the limit of such rotation of said cylinder the clip bar 156 is revolved by said cylinder into engagement with the clip bar pivoting roller 183 and the clip bar 155 is operated so that the clip opens upwardly.

Rotation of the impression cylinder 10 counterclockwise as described in the preceding paragraph causes the sprocket and chain drive 173 to revolve the sheet releasing blade 157 of the sheet feeding means counterclockwise as represented by the broken line arrow in Figure 3 to release and disengage the top sheet 154 of the stack 133 for gravity feed of said sheet to lodge its leading edge in said grip 155 as shown in Figure 3. During such rotation of the impression cylinder 19 the inking roller 191 and lower sheet discharge roller 187 are driven idly by belt 97.

As will now be seen, in the described limit of rearward overthrow movement of the type bed 31 and the limit of rotation of the impression cylinder 19 counterclockwise the parts of the press are in starting position for printing. Now by rotation of the impression cylinder 19 clockwise as indicated by the full line arrow in Figure 3, the cable will pull the type bed into the limit of its forward printing stroke, said bed will pull the carriage 33 forwardly against the front bumper bar 51 and then move relative to carriage 33 through a phase of overthrow forward movement limited by coaction of notches 61, 63 with axle shafts 49, and said notches 61, 63 and axle shafts 49 will coat during such overthrow movement of bed 31 to permit said bed to lower, all as shown in, Figure 5, so that said bed may move through its rearward return stroke idly as regards printing.

As the type bed 33 moves through its forward stroke the type 35 is inked by the inking roller 91 as shown in Figure 6 at the start of clockwise rotation of impression cylinder 19. The sheet grip 155 is revolved from engagement with roller 183 and closes to clamp the leading edge of the sheet to said cylinder 19 so that the sheet is pulled under and around said cylinder forwardly at the same speed as that at which the type bed 33 is pulled forwardly. Clockwise rotation of said cylinder is limited in the limit of overthrow movement of said bed forwardly by the notches 61, 63 and axle shafts 49 and cable 71. In the limit of clockwise rotation of said cylinder 19 the trailing edge of the printed sheet is above the sheet discharge rollers 85, 87 so that upon rotation of said cylinder 19 counterclockwise, see Figure 5, to return the parts to starting position the trailing edge of the printed sheet will be lowered between said rollers 185, 187 which are rotated in a manner which will be clear and at a faster rate of

speed than said cylinder to pull the sheet loose from the sheet grip 155 and from under the sheet guides 195 and feed it onto table 189.

The bolts 13, 15 and springs 9, 11 provide for yielding supporting the type bed 31 during printing according to requirements.

By latching the cradle 87 which is to say the inking means in upswung position, or detaching the same by removing shaft 89, a stencil sheet not shown may be used on said bed and the press converted into a duplicating machine.

The foregoing will suffice to impart a clear understanding of my invention.

Manifestly the invention is susceptible of modification without departing from the inventive concept and right is herein reserved to such as fall within the scope of the invention as herein disclosed.

What is claimed as new is as follows:

In a printing press sheet feeding mechanism, a rigidly mounted tray inclining downwardly and forwardly to an impression cylinder for containing a similarly inclined stack of sheets of paper for feeding of the sheets off the stack successively from the top of the stack by gravity to an impression cylinder, means for clamping the lower ends of the sheets of a stack comprising a terminal lip on said tray for overlying the lower end of the stack, and a false spring loaded bottom in said tray for supporting the stack of sheets of paper and coacting with said lip to releasably clamp the lower end of a stack of such sheets therebetween, a journalled shaft extending transversely over said tray for rotation in opposite directions respectively, means for rotating said shaft in opposite directions, a pair of collars spaced longitudinally of and fixed to said shaft for rotation in correspondence therewith, a pair of lateral studs on said collars for revolving in correspondence with rotation of the collars, a pair of clips swingably mounted on said studs and revolved thereby, a resilient blade clamped in said clips for revolving thereby into wiping engagement with the sheets of the stack idly in one direction of revolution of said clips, and a pair of lateral stop arms on said clips engaging said shaft in the other direction of revolution of the clips to prevent swinging of the clips and cause the blade to frictionally grip and buckle the sheets successively upwardly to release the sheets successively.
